UNITED STATES PATENT OFFICE.

WALLACE M. GRAY, OF CINCINNATI, OHIO.

INTERNAL-COMBUSTION ENGINE.

1,220,095.

Specification of Letters Patent. Patented Mar. 20, 1917.

Application filed April 11, 1916. Serial No. 90,496.

To all whom it may concern:

Be it known that I, WALLACE M. GRAY, a citizen of the United States, residing at Cincinnati, in the county of Hamilton and 5 State of Ohio, have invented certain new and useful Improvements in Internal-Combustion Engines, of which the following is a specification.

My invention relates to improvements in 10 internal combustion engines. One of its objects is to provide an improved engine of the two cycle type. Another object is to provide improved means to eject the products of combustion and to refill the cylinder with a 15 combustible mixture and scavenge the cylinder at each stroke of the plunger. Another object is to provide an economical engine of lower speed and more readily controllable than is attainable in the four cycle 20 type of engine, and therefore better adapted for marine and aviation purposes. Another object is to provide an engine capable of producing more power economically for a given weight of material in the engine. My 25 invention also comprises certain details of form, combination and arrangement all of which will be fully set forth in the description of the accompanying drawings, in which:

30 Figure 1 is a central vertical section through a combustion engine embodying my invention, being a section on line $z-z$ of Fig. 2.

Fig. 2 is a central vertical section on line $v-v$ of Fig. 1 and illustrating another position of the parts.

Fig. 3 is a horizontal section through the cylinder on line $x-x$ of Fig. 1.

Fig. 4 is a horizontal section through the 40 cylinder on line $y-y$ of Fig. 1.

The accompanying drawings illustrate the preferred embodiment of my invention, which I have illustrated applied to a single cylinder, but any desired number of cylinders may be employed and connected to a single shaft.

In the accompanying drawings A represents the crank casing or base of the machine. B represents the cylinder mounted 50 thereon and D the main crank shaft which is journaled at opposite ends in the casing A. A plunger E is pivotally connected to a link or pitman 2 which is journaled upon

the crank 3 of the crank shaft D, and said plunger is adapted to reciprocate between 55 certain limits within the cylinder, as for instance between the upper limit 4 and the lower limit 5. The plunger E is provided with piston rings 6 to provide a gas tight joint with the inner wall of the cylinder. 60

Mounted in the cylinder above the plunger E is a supplemental plunger H which loosely fits the cylinder walls and is provided with a stem or rod 7 which has a close sliding fit in a central perforation 8 axially 65 through the plunger E, so that there is practically no leakage of gas to or from the cylinder through the perforation 8. Oil ports 8' serve to lubricate the rod 7 in the perforation 8 from the splash system of the 70 crank case. A lever 9 is rigidly connected to an axle 10 journaled in the casing A, and the free end of said lever is slotted and connected by a pin 11 or similar means to the lower end of the rod 7 within the casing A. 75 For this purpose the link or pitman 2 is preferably forked or divided at its upper end to provide space for the rod 7 and lever 9. A spring actuated plunger 12 seated in a housing 14 attached to casing A engages 80 the lever 9 through the upper portion of its movement to hold the lever 9 in contact with its cam and to insure a perfect contact between the main and supplemental plungers at the upper limit of their strokes, and expelling all of the gas from between said 85 plungers before the gas is fired. A cam 17 is mounted upon a shaft 18 journaled in the casing A and driven at the same rate of speed as the crank shaft from said crank 90 shaft by means of a pair of gears 19 and 20. The cam 17 engages the lever 9 to lift said lever and with it the supplemental plunger H. The cam 17 during another portion of its revolution frees itself from and moves 95 out of the path of lever 9 leaving lever 9 and supplemental plunger H free to move with the main plunger E. The cylinder B is provided with a fuel supply port preferably comprising an annular recess or passage 22 100 from which a series of slots or ports 24 lead the fuel in gaseous form into the cylinder. The chamber 22 and ports 24 should be of ample capacity to quickly supply fuel to the cylinder. The ports 24 are located directly 105 above the lower limit of movement of

plunger E and below the lower limit of movement of the supplemental plunger H. At the upper end the cylinder is provided with a series of channels or raceways 25 in its interior wall, and located opposite the upper limit of movement of the plunger H.

An exit valve 26 preferably of ample capacity and preferably located and seating against the cylinder head is provided to 10 relieve the pressure in the cylinder and permit the spent or burnt gasses to escape into the chamber 27 and thence to the atmosphere. As illustrated the valve 26 is spring controlled to close it, and is opened by 15 means of a tappet lever 28 one end of which is pivotally connected to the cylinder and the opposite end is connected to a rod 29 which leads to and is actuated by a cam carried by the shaft 18 outside of the casting A. If desired, however, the exit valve 20 may be positively operated, or opened and closed in synchronism with the movements of the crank shaft by any suitable valve actuating mechanism.

25 The upper limit of movement of the supplemental plunger H is indicated by 30 and the lower limit of its movement, when the lever 9 rests upon the hub of cam 17 is indicated by 31.

30 In operation on the downward stroke of the plungers, before the plunger H reaches its lower limit of movement, the valve 26 opens and relieves the cylinder from pressure. The hub of cam 17 then engages lever 9 to limit the downward movement of plunger H, with the plunger H close to and above the inlet ports 24. When the plunger H reaches its lower limit of movement the crank center 3 of the 35 plunger E is in position to intersect with dotted line r, and as the crank shaft continues to move the two plungers separate and plunger E moves down at a relatively 40 slower rate of speed to uncover the inlet ports 24.

45 As soon as plunger E commences to uncover the inlet ports 24 the cam 17 commences to act on the lever 9 and causes the supplemental plunger H to rise quickly to 50 the position Fig. 1, which is near the upper limit of its stroke, thereby expelling nearly all of the burnt gases and drawing in, in its rear a fresh charge of combustible gas. The plunger H comes practically to rest 55 opposite the raceways 25 as illustrated in Fig. 1 until the main plunger E moves upward and closes the inlet ports, which it continuously covers until its return stroke, and compresses the charge which forces the combustible gases above plunger H and in position 60 to be ignited at the spark plug 34.

65 The plunger E continues to rise until it finally expels all the gases from between the plungers and overtakes the plunger H which is then carried forward by and on

the upper face of plunger E to the upper limit of movement of the respective plungers, when the compressed charge is fired and the two plungers move downwardly together, being driven by the energy of the 70 exploded gas, to a point where the exit valve is opened and the pressure relieved, when the two plungers again separate as above described ready to repeat the operation.

The mechanism herein illustrated and described is capable of considerable modification without departing from the principle of my invention.

Having described my invention, what I claim is:

1. In a two cycle internal combustion engine, a cylinder having an inlet port near one limit of the plunger movement and an exit port near the opposite limit of the plunger movement, a main plunger connected to a crank shaft and having a reciprocating movement in said cylinder to open and close said inlet port, a valveless supplemental reciprocating plunger movable away from said main plunger when said inlet port is uncovered by the main plunger to eject the spent gas and to introduce fresh combustible gas in advance of the main plunger at each cycle of movement thereof, and ports in the cylinder wall at 80 one end thereof to enable the fresh charge to pass said supplemental plunger.

2. In a two cycle internal combustion engine a cylinder having inlet and exit ports located near opposite limits of the plunger movement, a main reciprocating plunger, a valveless supplemental reciprocating plunger movable independently of said main plunger through a portion of the cycle of movement of said main plunger to 90 eject the spent gases from the cylinder and introduce a fresh charge of combustible gas into the cylinder in advance of the forward movement of the main plunger, and means at one end of the cylinder to pass the fresh 95 charge around said supplemental plunger.

3. In a two cycle internal combustion engine a cylinder having an inlet port near one limit of the plunger movement and an exit port and by-pass ports near the opposite limit of the plunger movement, a main reciprocating plunger, and a light weight valveless supplemental reciprocating plunger movable independently of said main plunger through a portion of the cycle of movement 105 of said main plunger to eject the spent gases from the cylinder and introduce a fresh charge of combustible gas into the cylinder in advance of the forward movement 110 of the main plunger.

4. In a two cycle internal combustion engine, a cylinder having an inlet port near one limit of the plunger movement and an exit port and by-pass ports near the opposite limit of the plunger movement, a main 120

reciprocating plunger to cover and uncover said inlet port, a valveless supplemental reciprocating plunger, and means to drive said supplemental plunger in the opposite direction to that of the main plunger through a portion of the cycle of movement of said main plunger to eject the spent gases from the cylinder and to introduce a fresh charge

of combustible gas in advance of the main plunger.

In testimony whereof I have affixed my signature in the presence of two witnesses.

WALLACE M. GRAY.
